UNITED STATES PATENT OFFICE

98,328

DESIGN FOR A COMBINATION ASH TRAY AND LIGHTER

William A. Inglis and Edwin E. Bathke,
Los Angeles, Calif.

Application August 7, 1935, Serial No. 58,005

Term of patent 7 years

To all whom it may concern:

Be it known that we, William A. Inglis and Edwin E. Bathke, both citizens of the United States, residing at Los Angeles, county of Los Angeles, in the State of California, have invented a new, original, and ornamental Design for Combination Ash Tray and Lighter, of which the following is a specification, reference being had to the accompanying drawing, forming a part thereof.

Figure 1 is a perspective view of our combination ash tray and lighter showing our new design; and

Figure 2 is a perspective view of the reverse side of our invention.

We claim:

The ornamental design for a combination ash tray and lighter as shown.

WILLIAM A. INGLIS.
EDWIN E. BATHKE.
